CUSHIONING MECHANISM

Donald S. Barrows, Rochester, N. Y., assignor to
The Symington Company, New York, N. Y., a
corporation of Maryland

Application May 25, 1929, Serial No. 365,931

10 Claims. (Cl. 213—22)

This invention relates to friction shock absorbing mechanism and its arrangement with railway draft rigging so that it permits greater travel of the coupler under buff than under draft, the greater coupler movement under buff being resisted by a greater shock absorbing capacity of the mechanism than is interposed to movement under draft.

The principal object of my invention, generally considered, is to provide a preferably double-ended cushioning mechanism, the parts of which are adapted to operate in series in association with the sills of railway rolling stock, so that the mechanism will function to provide greater energy absorbing capacity and movement under buff than under draft.

Another object of my invention is the provision of cushioning mechanism involving a body portion with a friction post extending therefrom and received in a freely open draft gear pocket between sills, a stop member being provided for holding said friction member against forward movement, wedges being provided engaging said post for generating frictional resistance, springs serving to effect release of the mechanism, and a follower casing engaging the wedges and fitting over the ends of said post, said mechanism being embraced by a yoke and limited in rearward movement by a backstop, said yoke being connected to an associated coupler by a draft key or the like.

A further object of my invention is the provision of double-ended cushioning mechanism comprising a friction member formed as a slotted body portion with friction posts extending both ways therefrom, wedges engaging said friction posts, intermediate followers engaging the inner ends of said wedges, release springs disposed between said body portion and followers, follower casings engaging the outer ends of said wedges and fitting over said posts, and means for holding the parts of said gear in assembled position.

Other objects and advantages of the invention relating to the particular arrangement and construction of the various parts will become apparent as the description proceeds.

Referring to the drawing illustrating my invention, the scope whereof is defined by the appended claims.

Figure 1 is a partial side elevational view and partial vertical longitudinal sectional view of one form of my cushioning mechanism shown assembled with associated draft rigging, portions of the associated cheek plates and backstop being diagrammatically illustrated.

Figure 2 is a fragmentary plan of the mechanism shown in Figure 1.

Figure 3 is a transverse sectional view on the line 3—3 of Figure 1, looking in the direction of the arrows.

Figure 4 is an end elevational view of the cushioning mechanism with the follower casing removed.

Referring to the drawing in detail, like parts being designated by like reference characters, there is shown one embodiment of my double-ended, series, friction draft gear 1, said gear preferably comprising a main friction member 2 having a body portion 3 slotted at 4 for receiving a draft key or other stop means 5 which extends through slots 6 in cheek plates 7 connected to associated draft sills 8 and holds the friction member 2 against movement under the action of draft forces while permitting rearward movement thereof under the action of buffing forces on account of the slots 6 being extended rearwardly of the normal position of the key 5.

Preferably extending both ways from the slotted body portion 3 of the friction member 2, and receiving the ends of said slot 4, are friction columns or posts 9 preferably double wedge shaped in cross section, as shown most clearly in Figure 4, providing V-shaped notches 10 in which fit friction shoes or wedges 11. The friction posts 9 preferably taper slightly from the slotted portion of the friction member 2, as illustrated particularly in Figure 1, but the V-shaped notches 10 are desirably formed at a uniform angle between the sides thereof so that the friction surfaces on the wedges or shoes 11 properly fit the corresponding friction surfaces on the posts in all positions.

For effecting release of the mechanism, coil springs 12 are desirably provided, above and below, or on either side of, said slot 4, thereby avoiding an increase in length of the mechanism, with their inner ends engaging abutments 13 on the main friction member 2 and their outer ends engaging intermediate followers 14 formed with friction surfaces 15 engaged by corresponding surfaces 16 on the friction shoes or wedges 11. If desired, pads 17 of bronze or any desired material may be inserted in the friction surfaces 15 on the followers 14 to improve the wear characteristics of the engaging parts.

Disposed at each end of the gear of the present embodiment is a follower casing 18 formed with a pocket 19 formed by bell mouthed or outwardly flaring portions 20 provided with friction surfaces 21 engaging friction surfaces 22 on the wedges or shoes 11. As in connection with the

100

105

110

followers 14, the follower casings 18 may likewise be provided with wearing inserts 23 for improving the wear characteristics with respect to the associated wedges 11. In order to maintain the 5 parts of the gear 1 in assembled relation even when disconnected from the associated mechanism, and to prevent the associated parts at the coupler end from separating from the gear proper when the coupler butt leaves this end of the 10 gear under pull, two pair of rods or bolts 24 are desirably provided extending through the follower casings 18 and the abutments 13 on the main friction member 2, the pair at the front or coupler end being preferably at diagonally opposite corners from the pair at the rear or backstop end. Each pair of said members 24 preferably extends from the abutments 13 to one of the follower casings 18, although if desired full length bolts may be employed. Each bolt may 15 be headed at one end, with a nut 25 or other securing means at the other end, or both ends may be threaded and have nuts 25 or the like applied thereto.

One way of utilizing the shock absorbing mechanism is to connect it to an associated coupler 26, which, in the present embodiment, is illustrated as being a swivel butt coupler, although I do not wish to be limited to this showing, and to provide a horizontal yoke 27 surrounding the mechanism 1 20 and an associated rear follower 28 with the looped or rear end 29 disposed between said follower and an associated backstop 30, or other means for limiting rearward movement of the mechanism, and connecting said yoke to the coupler 26 by a 25 front draft key 31 or other means for harnessing the parts together. It will, of course, be understood that the yoke 27 is slotted, as indicated at 32, for receiving the key 5 which connects the mechanism to the cheek plates 7 and associated draft 30 sills 8. The cheek plates 7 may be extended forwardly and correspondingly slotted to receive the ends of the key 31.

From the foregoing description, it will be seen that under the action of draft forces, the main 45 friction member 2 is held stationary by the key 5, and the coupler 26 pulls the yoke 27 forwardly through the connecting key 31 moving the rear follower 28 and pushing the rear follower casing 18, associated friction shoes 11, and intermediate 50 follower 14 over the rear friction post 9 compressing the rear releasing springs 12, and thereby actuating only the rear cushioning mechanism or rear half of the double-ended gear 1 utilizing only one-half the total capacity of said gear which 55 at the same time permits only one-half of the movement permitted upon a full compression of the gear.

Under the action of buffing forces, however, the 60 butt of the coupler 26 engages the front follower casing 18 pushing it and the associated friction shoes 11 and intermediate follower 14 over the front friction post 9, compressing the front release springs 12, simultaneously moving the main friction element 2 rearwardly so that the rear friction post 9 thereof is forced into the rear follower casing 18 sliding between the rear wedges or shoes 11 through the intermediate follower 14 and compressing the rear release springs 12, so 65 that a full compression of the gear is permitted. 70 On account of this action under buff, not only is an increased energy absorbing capacity provided, but a coupler travel is permitted equal to the sum of the travels permitted by the friction elements at each end of the gear. Although for 75 convenience and economy in manufacture the

gear is desirably made symmetrical so that the travel and capacity provided by each end is substantially identical, yet this is not essential in accordance with the broad aspect of my invention, so that the capacities and travels of the two ends 80 of the gear may be equal or different as desired.

From the foregoing description taken in connection with the accompanying drawing, it will be apparent that I have devised a form of cushioning mechanism which is double-ended, with the parts in each end adapted to be actuated in series preferably under the action of buffing forces while the parts at one end only are preferably actuated under the action of draft forces. Although I have shown a double-ended gear with the main friction element slotted for receiving a key, disposed between the release springs, for connecting the same to associated cheek plates and/or sills of a car, it will be understood that, if desired, a similar construction may be employed with a single ended gear as such a connection is admirably suited for connecting the main friction element with respect to the car underframe whether said element is single or double.

I have illustrated a preferred embodiment of my invention, but it will be understood that I do not wish to be limited to the form shown, as modifications may be made within the spirit and scope of the appended claims without departing 100 from my invention.

Having now described my invention, I claim:

1. In railway draft rigging, in combination with sills providing a freely open draft gear pocket, a double-ended draft gear comprising a body portion with a friction post extending both ways therefrom, a stop member passing through said body portion for holding it against forward movement, wedges engaging said posts, intermediate followers engaging the inner ends of said wedges, release springs disposed between said followers and the body portion, follower casings engaging outer portions of said wedges and fitting over the ends of said posts, a yoke embracing said mechanism, a backstop adapted to engage the rear end of said yoke for limiting rearward movement of said mechanism, a coupler adapted to engage the forward portion of said mechanism, and a key for connecting said coupler and yoke.

2. In railway draft rigging, in combination with sills providing a freely open draft gear pocket, a double-ended draft gear comprising a main friction member formed with a friction post extending forwardly and rearwardly therefrom, friction shoes engaging said posts, intermediate followers engaging the inner ends of said shoes, release springs disposed between said followers and main friction member, a stop member disposed between said release springs for holding said main friction member against movement in one direction while permitting movement in the other direction, follower casings engaging outer portions of said shoes, and fitting over the ends of said posts, yoke acting means surrounding said mechanism, means adapted to engage the rear of said means for limiting rearward movement of said mechanism, a coupler adapted to engage the forward end of said mechanism, and means for connecting said coupler and yoke.

3. In railway draft rigging, in combination with sills, cushioning mechanism received between said sills and comprising a main friction member involving a body portion and friction posts extending both ways therefrom, a stop member inter-

- secting said friction member for holding it against movement in one direction, friction shoes engaging said posts, means for effecting release of said shoes, follower casings engaging said shoes and fitting over the ends of said posts, a yoke surrounding said mechanism, a backstop for limiting rearward movement of said yoke and associated mechanism, a coupler disposed in abutting engagement with the forward portion of said mechanism, and means for connecting said coupler and yoke. 80
4. In railway draft rigging, in combination with sills, a double-ended draft gear comprising a main friction member having a body portion and friction posts extending forwardly and rearwardly therefrom, means intersecting said posts for preventing movement of said member in one direction while permitting movement in the other direction, friction shoes engaging said posts, release springs engaging said main friction member and acting to effect release of said shoes, follower casings engaging outer portions of said shoes and fitting over the ends of said posts, a yoke surrounding said mechanism, a backstop adapted to engage the rear end of said yoke for limiting rearward movement of said mechanism, a coupler adapted to engage the forward portion of said mechanism, and means for connecting said coupler and yoke. 90
5. Cushioning mechanism comprising a main friction member having a body portion with friction posts extending both ways therefrom, said body portion being slotted for receiving an associated draft key, wedges engaging said posts, intermediate followers engaging the inner ends of said wedges, release springs disposed between said followers and body portion, and follower casings engaging outer portions of said wedges and fitting over the ends of said posts. 95
6. Cushioning mechanism comprising a main friction member having a body portion with a friction post extending both ways therefrom, said friction member having a slot extending transversely therethrough and into said post for receiving means for connection with associated draft sills, friction shoes engaging said post, intermediate followers engaging the inner ends of said shoes, release springs disposed between said followers and body portion, follower casings engaging outer portions of said shoes and fitting over the ends of said post, and means passing through 100
- said follower casings and friction member for holding the parts assembled. 85
7. Cushioning mechanism comprising a friction member with a body portion slotted to receive a draft key and forming abutments for release springs on either side and friction posts extending forwardly and rearwardly therefrom, wedges engaging said posts, intermediate followers engaging the inner ends of said wedges, release springs disposed between said followers and abutments, follower casings engaging outer portions of said wedges and fitting over the ends of said posts, and means for holding the parts of the mechanism in assembled relation comprising a pair of members extending from diagonally opposite corners of a spring abutment portion to the follower casing at the other end of the mechanism and another pair of members extending from the other diagonally opposite corners of the other abutment portion to the other follower casing. 95
8. Cushioning mechanism comprising a main friction member involving a body portion with a friction column extending forwardly and one extending rearwardly therefrom, said body portion being slotted for receiving an associated draft key, wedges engaging said friction columns, resilient means acting on said wedges, and follower casings engaging outer portions of said wedges and receiving the outer ends of said columns. 100
9. Cushioning mechanism comprising a main friction member formed with a slot adapted to receive a draft key for connection with associated sills and friction posts extending both ways therefrom, wedge members engaging both of said posts, intermediate followers engaging the inner ends of said wedge members, resilient means acting on said followers for effecting release of the mechanism, said resilient means lying on either side of said slot to avoid increasing the length of said mechanism, and follower casings engaging said wedge members and fitting over the ends of said posts. 105
10. Cushioning mechanism comprising a main friction member slotted for receiving a draft key and having friction posts extending both ways from said slotted portion, wedges engaging said posts, release springs for said wedges, and follower casings engaging said wedges and fitting over the ends of said posts. 110
